MECHANICAL FIGURE TOY OR SIMILAR ARTICLE

Filed June 20, 1940

FIG. 2

FIG. 1

By

Inventor
IVAR E. NORDSTROM

Attorney

Richard S. Hayes

UNITED STATES PATENT OFFICE

124,224

DESIGN FOR A MECHANICAL FIGURE TOY OR SIMILAR ARTICLE

Ivar E. Nordstrom, Falconer, N. Y.

Application June 20, 1940, Serial No. 93,147

Term of patent 7 years

To all whom it may concern:

Be it known that I, Ivar E. Nordstrom, a citizen of the United States, residing at Falconer, in the county of Chautauqua and State of New York, have invented a new, original, and ornamental Design for a Mechanical Figure Toy or Similar Article, of which the following is a specification, reference being had to the accompanying drawing, forming part thereof, and in which

Figure 1 is a side elevational view of a mechanical figure toy or similar article, showing my new design;

Figure 2 is a front elevational view thereof.

I claim:

The ornamental design for a mechanical figure toy or similar article, as shown.

IVAR E. NORDSTROM.
